JOHN MACCORMACK, OF BROOKLYN, NEW YORK.

GAME APPARATUS.

1,259,888.

Specification of Letters Patent. Patented Mar. 19, 1918.

Application filed September 25, 1916. Serial No. 122,138.

To all whom it may concern:

Be it known that I, JOHN MACCORMACK, a citizen of the United States of America, residing at New York city, borough of Brooklyn, in the county of Kings and State of New York, have invented certain new and useful Improvements in Game Apparatus, of which the following is a specification.

My invention relates to a game apparatus

10 and a prime desideratum is to provide one embodying a principle adapting it for the pleasure and amusement of both young and old and to embodiment in toy form if desired.

15 The objects are to provide the game apparatus with a depository for disposition at an angle to a board over which projectiles are bowled or propelled toward the depository so that the projectiles will drop into the depository when gravity is acting with the greatest force to deflect the projectile from its course or trajectory; to provide projectile-receiving pockets in the depository and the pockets preferably in different sizes so 20 as to render it more difficult to lodge the balls or projectiles in one or more of the pockets as compared with the remainder; to provide the game as a toy utilizing a box having the depository foldably pivoted thereto and having an upstanding flange thereon engaged by a foldable strut or support for the depository to support the depository in an inclined position and to provide a depository, its support and the box 25 as a foldable structure.

With the above and additional objects, such as will hereinafter appear, in view, the invention has been embodied in one form as illustrated in accompanying drawings and 30 described hereinafter.

In said drawings:

Figure 1 is a longitudinal sectional view of the game apparatus showing several projectiles lodged in the depository;

45 Fig. 2 is a top or plan view of the game apparatus, and

Fig. 3 is a plan view of a score sheet which may be used.

Referring specifically to the drawings, 50 wherein like reference characters designate like or similar parts, the game is played with the aid of suitable projectiles like balls indicated at 4 which are manually propelled toward a depository 5 over an alley or way 55 defining the trajectory. In the drawings, I have shown the game apparatus as a toy

but a limitation in this respect is not to be implied since an alley may be used such as that employed for the game of ten pins. In the present instance, however, the alley 6 is 60 formed of a box, which may be of pasteboard, and which is bendable intermediate its edges along the dotted lines 7 so as to permit folding of the apparatus into compact form. It will be noted that an up- 65 standing flange 8 is provided at one end and partly at the sides of the board 6 while an upstanding flange 9 is provided at the other end and partly at the sides of board 6. It is to be noted that when the parts are folded 70 as suggested, the flange 9 fits intermediate or within the flange 8 and to facilitate folding, gaps are provided at 10 intermediate the flanges 8 and 9 and the lines 7.

The depository 5 is preferably disposed 75 at an angle as illustrated in the drawings. This depository may be of any suitable construction. For instance it may comprise a receptacle 11, in the case of the toy apparatus having upstanding sides and ends to 80 which a cover plate 12 is connected and spaced from the bottom, and preferably projects beyond the side of the receptacle 11 as at 13. Portion 13 is hinged in any suitable manner, as at 14 so that when the box 85 is folded, the depository may be swung back in order that the plate 5 may rest flat against the board 6. One bottom side edge 15 of the receptacle 11 engages the board 6 when the depository is in an inclined position in 90 order to help maintain it in such position. However, a suitable strut or support is provided at 16 being hinged or pivoted at 17 to the receptacle 11 and at its other end being adapted to abut the flange 9 at the rear end 95 of the board.

Plate 12 is provided with a suitable number of pockets 18 in the form of annular openings into which the trajectory balls 4 may be propelled. These openings or 100 pockets differ in size as shown in the drawings, so that it is more difficult to lodge the projectiles in certain pockets than it is in others. Any suitable rules may be devised under which the game is played but it 105 is preferable that the score for the projectiles entering the pockets will increase according to the degree of difficulty usually encountered in placing the projectiles therein. For instance the central or smallest 110 opening has the numeral 25 placed opposite it to indicate that a score of 25 will be

counted for a projectile entering such pocket. It is also easier to lodge the projectiles in the lowermost pockets than in the uppermost pockets and therefore the score for projectiles entering the lowermost pockets is 5 as indicated and for the uppermost pockets is 15 as indicated. The pockets at the top and bottom are greatly superior in size to the central pocket and this is for 10 the additional purpose of readily accommodating two or more projectiles in the marginal pockets so that if two or more projectiles do enter the same pocket, the player may be penalized according to the rules of 15 the game; for instance to the extent that no score is to be counted as a result.

As the form of apparatus illustrated is sold, the depository is packed flat and intermediate the sections of the box. The box 20 is first opened so as to be in the position shown in Figs. 1 and 2 after which the depository is swung upwardly to the inclined position shown and strut or support 16 placed in engagement with flange 9' to brace 25 it. The players, of the number and according to the rules of the game, may then manually propel the projectiles or balls 4 along the board 6 which in their trajectory may slide upwardly on the inclined plate 12 and 30 enter the pockets 18 which will count or score according to the rules of the game. Any suitable score sheet may be used; for instance that illustrated in Fig. 3 and which contains five blank frames in which each 35 player may indicate his score. This sheet is shown merely by way of suggestion as any suitable ones will suffice.

It is to be understood that changes may be resorted to within the spirit and scope 40 of the invention and especially the game apparatus is capable of use other than as a toy as hereinbefore stated.

It should also be noted that in playing the game, five balls are used, while five pockets 45 are provided in the plate or depository and in counting the game, five frames or boxes are used instead of ten as in the games of tenpins and duckpins. The numerical values of the pockets are also indicated by the 50 numeral five or factors thereof, and the game is, therefore, known as "Fives."

I claim:

1. A game apparatus comprising a base having parallel flanged sides, a projectile 55 depository arranged within said base at one end and extending entirely across the same, said depository being supported at an angle against one end of the base and having a double wall with pockets therein of varying 60 size.

2. A game apparatus to be played with five projectiles in the form of balls, comprising a base disposed on a horizontal plane and having parallel side and end flanges, 65 a projectile depository pivoted to the base

between the side flanges adjacent one of the end flanges, said depository having spaced walls with five projectile receiving pockets in the foremost wall, one of said pockets being smaller than the others and arranged 70 equi-distantly between the latter to accommodate only one ball, the other of said pockets being sufficiently large to accommodate two of said balls.

3. A game apparatus to be played with 75 five projectiles in the form of balls, comprising a base disposed on a horizontal plane and having parallel side and end flanges, a projectile depository pivoted to the base between the side flanges adjacent one of the 80 end flanges, said depository having spaced walls with five projectile receiving pockets in the foremost wall, one of said pockets being smaller than the others and arranged equi-distantly between the latter to accommodate 85 only one ball, the other of said pockets being sufficiently large to accommodate two of said balls, and means for foldably supporting said depository.

4. A game apparatus to be played with 90 five projectiles in the form of balls, comprising a base disposed on a horizontal plane and having parallel side and end flanges, a projectile depository pivoted to the base between the side flanges adjacent one of the 95 end flanges, said depository having spaced walls with five projectile receiving pockets in the foremost wall, one of said pockets being smaller than the others and arranged equi-distantly between the latter to accommodate 100 only one ball, the other of said pockets being sufficiently large to accommodate two of said balls, and a strut between the depository, the adjacent end flange to brace the depository in an inclined position relative to the base and to permit the same to be folded against the base.

5. A game apparatus to be played with five projectiles in the form of balls, comprising a base disposed on a horizontal plane 110 and having parallel side and end flanges, a projectile depository pivoted to the base between the side flanges adjacent one of the end flanges, said depository having spaced walls with five projectile receiving 115 pockets in the foremost wall, one of said pockets being smaller than the others and arranged equi-distantly between the latter to accommodate only one ball, the other of said pockets being sufficiently large to accommodate two of said balls, a strut between the depository, the adjacent end flange to brace the depository in an inclined position 120 relative to the base and to permit the same to be folded against the base, said base being adapted to be folded to inclose the depository strut, and balls used in the game.

6. A game apparatus including a projectile depository, said depository having a plate projecting beyond one side edge, a 130

board, the projecting portion of said plate engaging said board, and the bottom edge of said depository adjacent said projecting portion also engaging said board, whereby the depository is maintained in a position at an angle to the trajectory.

7. A game apparatus including a board, said board having foldable sections, one section having a marginal flange, the other section having a marginal flange for disposition within the first mentioned marginal flange, a projectile depository having a receptacle with an edge engageable with one

of the sections, a support extending from said receptacle in engagement with one of said flanges, a plate for said receptacle having a projectile-receiving pocket, and said plate extending beyond one side of the receptacle and being pivoted at the edge beyond said receptacle to one of said sections. 20

In testimony whereof I affix my signature in presence of two witnesses.

JOHN MacCORMACK.
